UNITED STATES PATENT OFFICE.

WILLIAM FRANZ AND WILLIAM POPE, OF CRESTLINE, OHIO.

IMPROVEMENT IN KNITTING-MACHINE.

Specification forming part of Letters Patent No. **88,027**, dated March 23, 1869.

To all whom it may concern:

Be it known that we, WILLIAM FRANZ and WILLIAM POPE, of Crestline, in the county of Crawford and State of Ohio, have invented a new and useful Improvement in Knitting-Machines; and we do hereby declare that the following is a full, clear, and exact description thereof, which will enable others skilled in the art to make and use the same, reference being had to the accompanying drawings forming part of this specification.

This invention relates to improvements in knitting-machines, whereby it is designed to provide a convenient and simple arrangement by which a part of the needles of a rotary knitting-machine may be thrown out of action, to admit of narrowing and widening for forming the heels and toes of stockings, or for knitting other flat fabrics in strips.

Figure 1 represents an elevation of a circular-knitting machine, partly in section, having our improvement applied to it. Fig. 2 represents a horizontal section of the same, and Fig. 3 represents the foot of a stocking formed on our said improved machine.

Similar letters of reference indicate corresponding parts.

We have represented an annular groove, A, in this instance, for the reception of the right-angled shanks of the needles, to hold them out of action, as formed by a recess in the lower face of a ring, B, arranged above the cam-cylinder C, the upper face of the cam-cylinder forming the lower wall of the groove; but the said groove may also be formed wholly in the cylinder above the cam-groove, if preferred. D represents a vertical groove, connecting the cam-groove and the annular groove A.

When the tubular portion of a stocking has been formed to the point represented at a, Fig. 3, in order to shape the heel, we raise about half of the needles out of the cam-groove, leaving the stitches on them, by turning the cam-cylinder so as to bring the vertical groove successively opposite the right-angled shanks of the needles, and raise them by

hand, to engage them in the annular groove A, when the cylinder is moved, so as to carry the vertical groove D beyond the said shanks. The yarn is then taken out of the carrier, and the cam run backward once around, in order to throw the latches over the loops of yarn on the needles. Then we carry the yarn back around the outside of the needles to the last needle that is down, turn the machine backward half around, take up one needle on each side, put the yarn in the carrier again, and turn forward half around; then go back again, as before, and so on until ten (more or less) needles on each side have been taken up from the commencement of the heel. We then commence putting the needles down again, in the same manner that they were taken up, until the ten or other number taken up are thrown down. Every time a needle is put down the thread must be carried over it to make the stitch. Then we put all the needles down, and knit forward until the foot is formed. The toe is then made up, the same as the heel, except that instead of taking up about ten needles we take up all but about six or eight, and then put down again, the same as in making the heel, until we have arrived at the point where the toe was commenced. We then put all the needles down, and run the work off by turning once around without the thread in the carrier. The toe is then closed up by hand across the bottom by bringing the two sides together, and looping the stitches together, or otherwise joining them.

Having thus described our invention, we claim as new and desire to secure by Letters Patent—

The ring B, having the annular groove A, in combination with the cam-cylinder C, provided with the vertical groove D, substantially as described, for the purpose specified.

WILLIAM FRANZ;
WILLIAM POPE.
